UNITED STATES PATENT OFFICE.

AUGUSTUS SEAVER, OF BOSTON, MASSACHUSETTS, ASSIGNOR OF ONE-HALF
TO CHARLES D. WOOD, OF LINCOLN, RHODE ISLAND.

DESIGN FOR A LAMP-SHADE.

SPECIFICATION forming part of Design No. 23,965, dated January 29, 1895.

Application filed November 2, 1894. Serial No. 527,773. Term of patent 14 years.

To all whom it may concern.

Be it known that I, AUGUSTUS SEAVER, a citizen of the United States, residing at Boston, in the county of Suffolk and State of Massachusetts, have invented and produced a new and original Design for Lamp-Shades, of which the following is a specification, reference being had to the accompanying drawings, showing a part thereof.

10 Figure 1 is a front elevation of a lamp-shade showing my invention. Fig. 2 is a sectional view of the same.

The leading feature of my design consists of a shade which is closed at one end and open 15 at the other end, and has a smooth unbroken exterior surface and is provided on its interior with prism-shaped ribs running substantially parallel with each other lengthwise of said shade, or from the closed to the open end 20 thereof, said prism-shaped ribs having their greatest width at a point intermediate of their ends and gradually tapering from said point to said ends, the ribs converging at the closed end of the shade.

A is the shade which is closed at one end 25 and open at the other end. On the interior of the shade are formed prism-shaped ribs a extending lengthwise of said shade, or from the open end to the closed end thereof. These ribs are widest at a point a' intermediate of 30 the ends b^2 , and taper from said point to said ends, the ribs converging at the closed end. The shade has a smooth unbroken exterior surface.

What I claim is—

35 The design for a lamp-shade, substantially as herein shown and described.

In testimony whereof I have signed my name to this specification, in the presence of two subscribing witnesses, this 30th day of 40 October, A. D. 1894.

AUGUSTUS SEAVER.

Witnesses:

A. D. HARRISON,
ROLLIN ABELL.
